[57] CLAIM

The ornamental design for a bicycle wheel, as shown and described.

DESCRIPTION

FIG. 1 is a side perspective view of a bicycle wheel showing the new design;

FIG. 2 is a side view of a bicycle wheel showing the new design;

FIG. 3 is a rear view thereof;

FIG. 4 is a front view thereof; and,

FIG. 5 is a top view thereof.

The broken line showing of the tire and of the bolt in the central hub area is for illustrative purposes only and forms no part of the claimed design.
